UNITED STATES PATENT OFFICE

165,957

SANTA CLAUS WINDMILL TOY

Charles F. Baumann, Oakland, and Verner
Schultz, San Leandro, Calif.

Application June 27, 1950, Serial No. 10,772

Term of patent 3½ years

(Cl. D34—15)

To all whom it may concern:

Be it known that we, Charles F. Baumann and Verner Schultz, citizens of the United States of America, residing respectively at Oakland and San Leandro, in the county of Alameda and State of California, have invented, a new, original, and ornamental Design for a Santa Claus Windmill Toy, of which the following is a specification, reference being had to the accompanying drawings, forming part thereof.

Fig. 1 is a front perspective view of a Santa Claus windmill toy showing our new design;

Fig. 2 is a side elevation;

Fig. 3 is a section taken on line 3—3 of Fig. 1.

We claim:

The ornamental design for a Santa Claus windmill toy, as shown.

CHARLES F. BAUMANN.
VERNER SCHULTZ.
